UNITED STATES PATENT OFFICE.

LEWES KNEEDLER, OF CALEDONIA, IOWA, ASSIGNOR TO FERNANDO F. LEATHERS, AND FREDERICK OFFENHAUSER, SR., AND JOHN N. LINEBURG, TRUSTEES.

BALANCED SLIDE-VALVE.

SPECIFICATION forming part of Letters Patent No. 349,048, dated September 14, 1886.

Application filed June 21, 1886. Serial No. 205,777. (No model.)

To all whom it may concern:

Be it known that I, LEWES KNEEDLER, a citizen of the United States, residing at Caledonia, in the county of Ringgold and State of Iowa, have invented certain new and useful Improvements in Balance Slide-Valves for Locomotives and other Steam-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention will first be described in connection with what is necessary to a full understanding thereof, and then pointed out in the claims.

20 Figure 1 of the drawings is a longitudinal vertical section, and Fig. 2 a perspective view.

In the drawings, A represents the ordinary slide-valve, with its subjacent escape-cavity. 25 I cast with this, and on the middle of the top thereof, the upright cylinder B, the escape-cavity extending up into the cylinder, for the purpose of giving a greater escape.

Over the cylinder B, I place the cast-metal hood C, filed to an accurate fit, so as to work freely over the cylinder when exposed to the greatest expansive heat which may occur in a steam-chest.

In the cylinder B, I make the annular groove b, in which is arranged suitable packing, preferably what is known as the "Dunbar" packing, and over this fits the hood C. Beneath the hood, over the cylinder, and between the hood and valve A, I arrange the ordinary yoke, D, which is turned and filed for the action of the valves, as well as connected to a valve-rod in the usual way, or in any approved manner. Between the yoke and hood is a space for the action of steam on the rim of hood. This gives an automatic movement to the hood and holds it in position against the top or cap of the steam-chest, so as to shut off all steam from the top of hood. The adjacent surfaces of the hood-top and lowest surface of chest are "trued," so as to make a steam-tight joint as the valve plays back and forth.

Near the top edge of cylinder, and in the bottom of the annular groove b, an elastic steel ring, b', is closely fitted, so as to spring at intervals and give an outward expansion. 55 Around this ring is placed the set of Dunbar packing, so as to make a steam-tight packing or joint with the inside surface of the hood.

The Dunbar packing and adjacent surface of hood are filed to make a steam-tight movable 60 joint, so as to permit of the motion of hood under the influence of the steam on its lowest rim.

On top of the cylinder are formed two cavities, b²b², in which I arrange springs E E, either 65 elliptical or spiral, to hold the hood against the lid or cap of the steam-chest when steam has been shut off. This prevents the hood from dropping away from the steam-chest, lid, or cap, and admitting air or steam. This makes 70 a balance slide-valve in which there will not be unequal wear, which greatly lessens the friction and strain on the valve-gear and the slipping of the eccentric; also, the quadrant for reversing lever may be used as well when 75 the throttle is open as when steam is shut off; also, steam riding and friction are to a great extent avoided. Thus it will be seen that my invention is characterized by great simplicity, little liability to get out of order, a great saving of fuel, a gain of power, a great reduction of friction, an equal wear, and great durability. Indeed, with care my valve will wear 80 out an engine with little or no repair.

Having thus described my invention, what 85 I claim as new, and desire to protect by Letters Patent, is—

1. The combination, with the cylinder and hood B C, of the elastic steel ring b', arranged in the annular groove b and surrounded by 90 packing, substantially as specified.

2. The combination, with a balance-valve, cylinder B, and hood C, of the springs E E, arranged in grooves or cavities in the top of cylinder, as and for the purpose described. 95

In testimony whereof I have affixed my signature in presence of two witnesses.

LEWES KNEEDLER.
